CHARLES WHITTIER, OF BOSTON, MASSACHUSETTS, ASSIGNOR TO HIMSELF AND
BENJAMIN F. CAMPBELL, OF SAME PLACE.

Letters Patent No. 83,811, dated November 3, 1868.

IMPROVEMENT IN STEAM-GENERATORS.

The Schedule referred to in these Letters Patent and making part of the same.

To all whom it may concern:

Be it known that I, CHARLES WHITTIER, of the city of Boston, in the State of Massachusetts, have invented certain new and useful Improvements in Steam-Generators; and do hereby declare the following to be a full, clear, and exact description thereof, reference being had to the accompanying drawings, and to the figures and letters marked thereon.

Of these drawings—

Figure 1 is a side elevation of the exterior shell of the generator;

Figure 2 is a side elevation of the interior shell thereof;

Figure 3 is a longitudinal vertical section of the whole generator; and

Figure 4 is a vertical cross-section thereof, taken in the line $z z$ of fig. 3.

Similar letters of reference indicate corresponding parts in the several figures.

The object of my improvements is to provide a generator for steam and water-heating purposes that will contain an increased heating-surface; that will more effectually utilize the products of combustion; and that will not permit of the escape, from the metallic surfaces into the surrounding atmosphere, of unhealthy gases. Previous to my invention the products of combustion in horizontal boilers passed from front to back through round tubes, placed immediately, or nearly so, in the rear of the fire-box, and then into the smoke-flue, carrying with them a large portion of caloric; or else the products passed from front to back, and then returned through flues to the front, such flues being placed wholly within the water-space, at or near the base of the generator, and then into the smoke-flue. Not only heat was thus lost, but the heating-surface was limited.

The general features of my invention consist in the construction of the ports, so that a good high combustion-chamber is obtained, the products of combustion passing about the tubes placed below the inner crown-sheet, the whole length of the generator, and at the same time along over the horizontal portion of a bridge-piece placed within the generator, at the back of the fire-box and ash-pit, until they are deflected down from the back end of the tubes, round underneath the lower horizontal surface of this bridge-piece, and then down the vertical surface contiguous thereto to the smoke-flue. Also, by making the generator of two shells so connected with each other, the water-tubes, and this bridge-piece, that there will be a free circulation of water and steam through these portions, resulting in the whole generator.

This construction serves not only to increase the heating-surface, but aids to prevent the escape of gases through any part of the generators, except that they pass into the water and steam-chamber, where they at once become neutralized, thus rendering the combustion

of anthracite coal free of the danger of its throwing off into the external atmosphere, in connection with caloric (which is frequently utilized for hot-air pipes, by surrounding the generator with a brick casing,) gases deleterious to health.

In the drawings, a represents the exterior shell of the generator, composed of wrought-iron, and having in one of its ends the fire and ash-door openings; b , the interior shell, composed of the same material, and being a counterpart of the exterior one, excepting that it is made smaller so as to form a water and steam-chamber between the two, of a convenient and proper size, thus permitting a free circulation of water and steam, about every portion of the generator, and around the fire and ash-doors and smoke-flue, as seen at $c c$, &c. These two shells are riveted or otherwise conveniently attached together at their base, and to casings placed around the fire-chamber, ash-pit, and smoke-flue openings.

Immediately at the rear of the fire-chamber and ash-pit, and forming the back thereof, is placed a bridge-piece d , composed of cast-iron; this bridge-piece extends up to the top of the fire-chamber, and then turns back in a horizontal position, or slightly depressed from such position, and runs back nearly to the rear of the inner shell, b . This bridge-piece lies wholly within the inner shell, but has perforations, or openings, in the inner shell, as shown at $e e$, &c., so as to permit of the free circulation of the water, from the water-chamber formed by the two shells a and b , through it. The casting composing this bridge-piece is, at its edges, properly riveted on to the inner shell, and is, of course, steam-tight at its edges.

Within the combustion-chamber, just below the crown-sheet, is a number of round tubes, $f f$, &c., properly inserted into the interior shell, and running from front to back thereof, so as to permit of the free circulation of water and steam through them, from the water and steam-chambers, and the free passage, outside, and between, and around them, below the crown-sheet, of the products of combustion.

The tubes are preferred, as before stated, to be inclined or depressed from front to back.

g is the smoke-flue, which passes through both shells a and b , and takes the products of combustion out from under and around the bridge-piece, after they have freely circulated about the same and the tubes $f f$, &c. h is the pipe which conducts the steam off into the radiators, placed in desired parts of the building, though I prefer to take the steam from the generators at a point nearer the back part, as it is there drier. Water is taken into the chamber of the generator at any proper and convenient point.

I give the tubes a slight incline or depressed position, from front to back, so that they will leave a good high combustion-chamber, and approach quite near

the bridge-piece at the rear end. The horizontal portion of the bridge-piece can be made to incline, so that it will be parallel with these tubes, as shown in the drawings.

The utility of this arrangement is evident from the fact that, as the water passes up through the rear ends of the tubes *f*, &c., it is commenced to be converted into steam, and when it reaches the front end, it passes more quickly and rapidly into the steam-chamber.

The products of combustion are more effective at this point, where steam is required to be made more quickly, and from here they pass along down and around the tubes, towards the back part, losing their greater effectiveness at a point where the generation of steam is least required, but still where it is necessary to have the pipes in as close and efficient contact with them as possible.

Claims

1. A bridge-piece, having water and steam-connections with a double shell, in combination with such double shell and water-tubes, constructed and arranged substantially as herein described.

2. The arrangement of the flues with reference to the double shell and bridge-piece, substantially as described.

3. The bridge-piece *d*, when constructed substantially as described, and placed in the rear of the firebox, to increase the heating-surface of the generator.

CHARLES WHITTIER.
